US0D1042495S

(12) United States Design Patent (10) Patent No.: US D1,042,495 S
(45) Date of Patent:  Sep. 17, 2024

(54) DISPLAY SCREEN OR PORTION THEREOF WITH GRAPHICAL USER INTERFACE

(71) Applicant: Apple Inc., Cupertino, CA (US)

(72) Inventors: Michael Charles Evashevski, San Francisco, CA (US); Russell Louis Kawabata-Perrett, San Francisco, CA (US); Mark David Majdanski, San Francisco, CA (US); Wyatt R. Mitchell, San Francisco, CA (US); Emmet Ray Smith, San Francisco, CA (US)

(73) Assignee: Apple Inc., Cupertino, CA (US)

() Term: 15 Years

(21) Appl. No.: 29/841,315

(22) Filed: Jun. 5, 2022

(51) LOC (14) Cl. 14-04

(52) U.S. Cl.

USPC D14/485

CLAIM

The ornamental design for a display screen or portion thereof with graphical user interface, as shown and described.

DESCRIPTION

The sole FIGURE shows a front view of a display screen or portion thereof with graphical user interface showing the claimed design.

The peripheral dashed broken lines depict a display screen or portion thereof, and form no part of the claimed design. The dashed broken lines within the peripheral dashed broken lines represent text or features which form no part of the claimed design.

1 Claim, 1 Drawing Sheet
